UNITED STATES PATENT OFFICE.

ROBERT G. FISHEL, OF CHICAGO, ILLINOIS.

DISPLAY SIGN AND MEANS FOR MOUNTING THE SAME.

Application filed January 13, 1926. Serial No. 80,893.

My invention relates to display signs and means for mounting the same. In its more specific aspect, the invention is concerned with a small advertising sign so constructed that it can be quickly and easily clamped to the top of the conventional cash register or checking register. By providing the signs with clamping means for attachment to cash registers, the sign has a ready and available support for mounting in practically all shops, stores and restaurants. When thus mounted on the register the sign is attention-getting because of its prominent position and its proximity to the indicating figures on the register.

It is one of the principal objects of the present invention to provide a simple and effective construction of sign mounting means and clamping devices therefor, which clamping devices will hold the sign securely on the register, and which will also be adjustable for adapting the unit for mounting on different types and sizes of registers.

It is a further object of the invention to provide fastening elements for these clamping devices which will prevent releasing of the clamping devices, at least with the tools ordinarily at hand. This is to prevent the shop keeper, after accepting the sign as a gratuity, from removing it before it has fulfilled its advertising function. Referring to the accompanying drawing illustrating my invention:

Figure 1 is a perspective view of a typical cash or checking register showing my improved sign mounted thereon.

Figure 2 is a fragmentary sectional view through one of the supporting standards and its associated clamping devices.

Figure 3 is a side elevational view of the standard and clamping means.

Figures 4 and 5 are detail views of one type of special screw for the clamping devices.

Figure 6 is a fragmentary sectional view illustrating another type of screw.

Figure 7 is a view generally similar to Figure 2 illustrating a modified construction of clamping device, and

Figure 8 is a transverse sectional view taken on the line 8-8 of Figure 7.

The types of cash or checking registers now in most prevalent use are typified by the register illustrated in Figure 1, these registers generally having a flat top surface 12 consisting of a pane of glass or a flat

metal plate. The present sign has been devised for mounting on this flat upper surface 12. In the usual construction this flat upper plate 12 projects slightly along its front and rear edges as indicated at 13-13 in Figure 2, and to those projecting ledges the sign can be securely clamped.

The sign comprises a plate or panel 14 on which appears the subject matter of the advertisement, this plate or panel being glass, metal, or any other preferred material. Supporting the plate at its ends are two uprights or standards 15-15. As shown in Figures 2 and 3, the inner face 70 of each upright is formed with a slot or groove 16 into which projects the ends of the sign panel.

Each upright or standard 15 has an arrangement of clamping devices whereby it can be fastened in erect position on the top surface 12 of the register. In the preferred embodiment these clamping devices comprise a clamping foot or rest 18 which is formed integral with the lower end of each upright 15, and a cooperating clamping section 19. Each clamping foot 18 is formed with a clamping hook 21 adapted to engage over the projecting edge 13 of the top surface 12. The separate clamping section 19 has a similar clamping hook 22 for engaging over the projecting edge 13 on the opposite side of the plate 12. These two clamping devices 18 and 19 have an extensive area of contact with the top surface 12 and afford a firm support for each upright.

The clamping portion 18 has a threaded bore 23 tapped into the inner end thereof. The other clamping member 19 has an apertured ear 24 extending upwardly from its inner end. A clamping screw 25 passes through this apertured ear and screws into the threaded bore 23 for drawing the two clamping sections into firm engagement with the edges of the top plate 12. The clamping screw 25 gives a considerable latitude of adjustment between the two cooperating clamp sections whereby the device can be clamped to top surfaces 12 of widely varying widths. When drawn together under the tension of the clamp screws, the clamping sections of both uprights rigidly hold the uprights against sliding movement on the top plate or any other movement by which the sign might be removed.

The sign is generally a gratuity to the shop keeper and it is desirable to prevent

his removing the sign any time at his pleasure. To this end the invention embodies improvements in the clamping screws 25 whereby the screws are rendered entirely irremovable or irremovable by the tools ordinarily at hand.

In the embodiment shown in Figures 4 and 5, these clamping screws have counter sunk heads 26 which engage in beveled recesses 27 in the clamping lugs 24, whereby only the end of the screw head is accessible after the clamps have been drawn up tight. Each screw head has a kerf therein one side of which, on opposite sides of the head, are milled or cut away. This leaves abrupt shoulders 29 facing in one direction by which the screw can be driven home by the ordinary screw driver to draw the clamps together. The cut away sides of the kerf leave sloping surfaces 31 with which the bit of the screw driver can have no effectual engagement. Thus after the screw has been driven home to hold the clamps in firm clamping engagement on the cash register, the screw can not be removed, at least by the ordinary screw driver.

Another form of clamping screw is illustrated in Figure 6. In this type, the screw has a spanner head 33 preferably of cylindrical form, having the spanner sockets 34 entering this cylindrical head radially. This type of screw can not be released except through the use of a special spanner wrench of proper size to engage these screw holes.

In Figures 7 and 8 I have illustrated a modified construction of clamping means wherein one clamp section affords guiding

support for the other clamp section. The clamp section 18 has a projecting end portion 36 of U-shaped section into which slides 40 the correspondingly shaped end 37 of the other clamp section 19. This affords a relatively long area of guided support between the two clamp sections and also encloses the shank of the clamping screw 25. This clamping screw preferably passes through an unthreaded hole 39 in the clamp section 18 and screws into a threaded bore 41 in the other clamp section, although this arrangement may be reversed if desired. This screw may be provided with a one-way kerf such as is shown in Figures 4 and 5 or may be provided with a spanner head such as is shown in Figure 6.

Having thus described my invention, what I claim as new and desire to secure by Letters Patent of the United States is:

In an advertising device, a pair of integral standards each having a flat foot at its base, said standards having longitudinal slots in their opposed sides, with an advertising plate adapted to be received in said slots, said foot having a guide formed therein, a clamping lug on said foot, a second clamping member sliding in said guide, and screw means enclosed in said foot for actuating said clamping member toward said lug, said screw means having a kerf without engaging shoulders to unscrew the same.

In witness whereof, I hereunto subscribe my name this 8th day of January, 1926.

ROBERT G. FISHEL.
